GEAR OPERATED PREDETERMINED
TORQUE RELEASE WRENCH

Harry C. Pedersen, Royal Oak, Mich., assignor, by
direct and mesne assignments, to Clyde Engi-
neering and Manufacturing Corporation, Royal
Oak, Mich., a corporation of Michigan

Application November 30, 1949, Serial No. 130,287

2 Claims. (Cl. 81—52.4)

1

This invention relates to power operated wrenches, the primary object of the invention being to provide means for automatically disconnecting the power from the wrench shank when the tool has operated to tighten a nut upon a bolt to predetermined torque setting.

An important object of the invention is to provide means for moving the coupling members to move the teeth of the coupling out of contact with each other after the nut driven by the wrench has been tightened as required, thereby eliminating wear on the teeth due to the rotation of the coupling members and teeth during overrunning of the clutch.

Another object of the invention is to provide means for adjusting the automatic throwout mechanism so that the throwout mechanism will operate when a nut has been tightened upon a bolt to a predetermined distance or torque setting.

Still another object of the invention is to provide an improved automatic power operated wrench which will be automatically rendered operable by the operator in placing the wrench upon a nut disposed on a bolt and applying pressure upon the wrench in the direction of the nut.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawings

Figure 1 is a longitudinal sectional view through a power wrench, constructed in accordance with the invention.

Fig. 2 is a sectional view taken on line 2—2 of Fig. 1.

Fig. 3 is a sectional view taken on line 3—3 of Fig. 1.

Fig. 4 is a side elevational view of the main or body portion of the wrench.

Fig. 5 is a sectional view through the upper portion of the wrench.

Fig. 6 is a perspective view illustrating the coupling member of the tool.

Referring to the drawings in detail a work turning element A of the wrench comprises a main shaft 5 carrying adjacent one end a driven head B. The shaft 5 is provided intermediate its ends with a threaded portion 6 with which

2

an adjustable stop collar 7 is threadedly engaged. The collar 7 is provided with threaded openings 8 and wrench openings 9, whereby the collar may be adjusted longitudinally of the main shaft 5 and held by means of set screws 10 positioned within the threaded openings 8.

This stop collar 7 provides a seat for one end of a compression coiled spring 11 which encircles the shaft 5 and the opposite end of said 10 coil spring bears against a bearing C comprising a steel washer 12 that in turn frictionally engages the bronze washer 13 that rests against a steel washer 14. The steel washer 14 is provided with an enlargement 15 that fits within a recess 16 formed in the lower end of a collar 17 which encircles the shaft 5 and forms a driving head D which is rotatable about and longitudinally movable relative to the shaft or work turning element A.

Surrounding the collar 17 and fixed thereto as by means of a key 22 is an outwardly extending annular ring 21 having formed in the end thereof adjacent the driven head B peripherally spaced recesses 18 of substantially rectangular form. 20 These recesses open through the adjacent end of the ring 21 for the reception of peripherally spaced fingers 28 which are carried by a driving element 26 which is mounted for rotation on the shaft 5 adjacent the driven head B on the side thereof remote from the driving head D. A suitable anti-friction bearing 33 provides the support for the driving element 26 on the shaft 5. Carried by the driving head D on the end thereof adjacent the driven head B is an annular row of tapered teeth 23 which as illustrated in Fig. 5 are adapted to mesh with cooperating teeth 24 on the driven head B. Said teeth 23 and 24 being held in meshing engagement under the influence of the spring 11 previously referred to. It will thus be seen that when the resistance to turning of the shaft 5 attains a predetermined value, the teeth 23 will ride against the inclined surfaces of the teeth 24 to cause a separation of the driving head D from the driven head B against the effort of spring 11. Formed in the ring 21 and extending radially therethrough adjacent one corner of each recess 18 is an arcuate recess 19 into which is fitted a roller 20. These rollers project radially outwardly beyond the periphery 25 of the collar 17, and secured in any suitable manner to the ring 21 in encircling relation to and overlying portions of the rollers 20 is an annular retainer 32 by means of which the rollers 20 are held in proper position in the recesses 19. As shown the rollers 20 lie in the path of

50

the fingers 28 so that when turning effort is applied to the driving element 26, the fingers will engage the rollers and cause the driving head D to rotate in unison with the driving element 26.

Carried by the fingers 28 and formed at the junctions of the trailing walls of the recesses and the ends of the fingers remote from the driving element 26 are inclined cam surfaces 29 which, when the teeth 23 and 24 approach maximum separation against the effort of the spring 11, engage the peripheral surfaces of the rollers 20 to exert further separating effort on the parts to completely separate the teeth so that the driving head D may rotate without turning the work turning element A and the points of the teeth 23 and 24 will be protected from wear. The driving element 26 is provided on the end thereof remote from that carrying the fingers 28 with clutch teeth 38 which are adapted to be engaged by the teeth 39 of a clutch member 40 which is mounted for rotation on an extension 42 of the shaft 5 and is coupled to a conventional driven gear 48 which is operatively connected through the drive gear 49 to the prime mover of the device.

In use it will be seen that as the teeth 39 of the clutch 40 engage the teeth 38 of the driving element 26, assuming of course that the prime mover is in operation, power will be transmitted through the fingers 28 to the head D by engagement with the rollers 20. In this driving operation, the teeth 23 will be held in mesh with the teeth 24 under the influence of the spring 11 so that driving effort will be transmitted to the shaft 5. When the resistance of the shaft 5 to turning attains a predetermined value, the inclined faces of the teeth 23 and 24 will tend to cause the driving head D to move longitudinally on the shaft 5 against the efforts of the spring 11 until the inclined cam numbers 29 on the fingers 28 attain a position which will cause them to ride on the rollers 20 and move the head D further against the effort of the spring 11 until the points of teeth 23 and 24 are free from one another to thus enable the driving head D to rotate without imparting any rotary motion to the driven head B.

While in the foregoing there has been shown and described the preferred embodiment of this invention it is to be understood that minor changes in the details of construction, combination and arrangement of parts may be resorted to without departing from the spirit and scope of the invention as claimed.

Having thus described the invention, what is claimed is:

1. In a power driven wrench, a main shaft, a driving member having teeth, keyed on the shaft, a driving sleeve loosely mounted on the driving member, said driving sleeve having extensions, a collar rotatably mounted on the main shaft, said collar including an inner section having teeth meshing with the teeth of the driving member, coupling the main shaft with said collar, said collar having cut away portions extending from one edge thereof, into which the extensions extend, bearings mounted within the cut away portions, said extensions engaging said bearings and rotating the collar and main shaft as the

driving sleeve rotates, an adjustable tension spring encircling a portion of the main shaft and bearing against the collar, thereby normally urging the collar towards the driving sleeve and connecting the teeth of the collar and driving sleeve, said extensions having rounded corners adapted to ride over the bearings, thereby disengaging the teeth of the driving member and collar, said extensions resting on the bearings and holding the teeth of the driving member and collar separated during continuous rotation of said main shaft.

2. In a torque wrench in which driving power applied to work is automatically discontinued when the resistance of the work to turning attains a predetermined value, said wrench comprising an elongated work turning element, a driven head fixed to said element, an annular row of teeth having oppositely inclined faces carried by and extending longitudinally from one side of said driven head, a driving head mounted on said work turning element for rotation thereabout and movement longitudinally thereon adjacent the driven head, an annular row of teeth having oppositely inclined faces carried by and extending longitudinally from the side of the driving head adjacent the driven head, a collar mounted on the work turning element in spaced relation to the driving head for adjustment longitudinally on said work turning element, a compression coiled spring encircling the work turning element and bearing on the collar and on the driving head for yieldingly holding the teeth of the driving head in mesh with those of the driven head whereby when the resistance to turning of the work turning element attains a predetermined value the teeth on the driving head will ride on the teeth of the driven head against the effort of the spring and turning effort on the work turning element will be discontinued despite the continued rotation of the driving head, rollers carried by and extending radially outwardly from the driving head, fingers carried by the work turning element for rotation thereabout, said fingers extending parallel with said work turning element and being adapted to engage the rollers for driving the driving head, and cam surfaces on the fingers for engaging the rollers and moving the driving head against the effort of the spring to completely disengage the teeth as they approach disengagement.

HARRY C. PEDERSEN.
